CASKET HANDLE

William Frederick Sheeley, Galesburg, Ill., assignor of one-half to Gale Davison, Galesburg, Ill.

Application November 12, 1935, Serial No. 49,374

12 Claims. (Cl. 16—112)

This invention relates to improvements in handles for bodies of the nature of caskets, and pertains particularly to an improved folding handle.

5 In the construction of caskets, two types of handles are used. In one type the handle comprises a bar running the length of the casket and secured by a rigid arm to the side wall of the same, while in the other type the bar is attached 10 to the casket wall by hinged arms so that when the handle or bar is released the arms drop to positions substantially parallel with the casket wall. The preferred form of handle is the one employing the arms rigidly attached to the casket, 15 but these are undesirable because of the fact that the box in which the casket is placed or the grave vault, must be made extra wide to compensate for the distance which the handle projects from the casket wall.

20 The present invention has for its primary object to provide an improved casket handle which has all of the desirable features of the fixed or rigid handle type with the advantage that it may be released and folded down against the side wall 25 of the casket so that the casket may be placed in a smaller vault or box than would be possible if the handle were fixed.

Another object of the invention is to provide a novel folding handle structure in which the 30 handle when raised for use or folded will be held tightly in position and cannot move or rattle.

Another object of the invention is to provide a 35 folding handle which when in position for use may be firmly secured and which is so designed that when released for folding it must be drawn outwardly before it can be lowered, thus assuring its remaining in place when it has been raised to the position in which it is to be used.

The invention will be best understood from a 40 consideration of the following detailed description taken in connection with the accompanying drawing forming part of this specification, with the understanding, however, that the invention is not confined to any strict conformity with the 45 showing of the drawing but may be changed or modified so long as such changes or modifications mark no material departure from the salient features of the invention as expressed in the appended claims.

50 In the drawing:

Figure 1 is a view showing a handle embodying the present invention partly in side elevation and partly in section.

55 Fig. 2 is a vertical sectional view through the

central part of the handle structure showing the same in raised position.

Fig. 3 is a view similar to Fig. 2, showing the handle lowered or folded.

Fig. 4 is a section on the line 4—4 of Fig. 1.

Fig. 5 is a view of the blank from which a portion of the handle structure is formed.

Fig. 6 is a view in elevation of the central part of the handle fixture showing the arm lowered.

Referring now more particularly to the drawing the numeral 1 indicates a portion of a casket upon which the handle embodying the present invention is shown applied. This handle comprises a body portion 2 which may be of any desired form and which in the present instance is shown as a pressed metal plate having a central 10 outstanding rib 3 which at its lower end merges into the shell body or portion indicated generally by the numeral 4 and consisting of a top wall 5 and depending side walls 6. This shell borders 20 an opening 7 in the body, and it is to be understood that this opening may be formed in any type of body without having the rib 3 but having the shell 4 formed integral with and projecting over the face of the body, or the shell may be 25 formed in any other desired manner. The side walls 6 of the shell 4 are provided with suitable apertures to receive a pin 8 which extends transversely of the shell between the walls and each side wall is pressed outwardly to form a recess 9 30 which opens from the forward edge of the wall, as illustrated in Fig. 6. One of these recesses is provided with a threaded aperture to receive a screw 10, the purpose of which will be herein- 35 after fully described.

The numeral 11 indicates generally a bar supporting arm. This arm is of hollow construction and is formed from a sheet metal blank of the character illustrated in Fig. 5. This blank before folding comprises an elongated strip of 40 material 12 which has laterally extending wings 13 at one end and at the opposite end wings 14 which are of less width than the wings 13. The body 12 is bent intermediate its ends to form a ring 15 through which the tubular handle or hand 45 grip 16 is extended and previous to the bending of this portion the wings 13 and 14 are bent to positions at right angles with the body 12 so that the wings 13 will be brought into overlapping relation with the wings 14 and secured thereto by 50 the tongues 17 which are formed integral with the wings 13 and which are extended into recesses 18 formed through the strip 12 at the end adjacent the wing portions 14. Each of the wings is 55 also provided with a slot 19 and these slots in

the wings 13 aline with the similarly formed slots in the wings 14 when the wings are folded as described and receive the bar or pin 8 upon which the arm 11 slides and oscillates.

5 The wing portions 13 of the strip 12 are located over the outer sides of the wings 14 and each of these wings 13 has a lug 20 formed upon its outer side, one of which has an aperture 21 formed therethrough. These lugs are adapted 10 to slide into the recesses 9 when the handle bar carrying arm is disposed in a position at right angles with the body 2 so as to act as a means for preventing the swinging downward of the arm. In order to retain the arm in position an expansion spring 22 is provided which is located 15 within the arm and has one end secured to the pin 8 while the other end is secured to the bottom wall of the arm by means of the integral tongue 23.

20 At its inner end of the top wall of the arm 11 is rounded off, as indicated at 24, while the bottom wall has a flange or tongue 25 formed thereon and extending across the end of the arm.

As shown in Fig. 2 the arm 11 when in raised 25 position extends at one end horizontally into the shell 4, the top wall of the arm abutting the outer edge of the wall 5 of the shell, while the bottom wall of the arm rests upon the lower edge of the opening 7 with the tongue 25 disposed within 30 the body 2. The arm 11 is drawn into the opening 7 by the spring 22, its movement inwardly being limited by the pin 8 in the alined slots 19 and when in this position the lugs 20 of the arm are disposed in the recesses 9, as previously 35 described.

It will thus be seen that when upward pressure is applied to the outer end of the arm 11 as by the lifting of the casket body by means of the hand bar or grip 16, the top wall of the arm 40 will be forced against the edge of the wall 5 while the lower wall of the arm will bear firmly against the lower edge of the opening 7.

In order to release the arm so that the same 45 together with the bar 16 may be folded down, the arm must first be drawn outwardly from the opening 7 while at the same time its outer end is depressed the lugs 20 sliding out of the recesses 9. This action will effect the relative 50 movement of the pin in the slots 19 and the further tensioning of the spring 22 and at the same time it will bring the tongue 25 against the inner edge of the lower wall of the opening 7 thus effecting the holding of the rear end of the arm at its lower edge to facilitate the swinging outwardly and downwardly of the upper portion.

The final position of the arm with the bar 16 is illustrated in Fig. 3, where it will be seen that the curved portion 24 lies beneath the outer edge of the wall 5 of the shell and the pin upon which 60 the arm slides and oscillates is disposed adjacent the ends of the slots 19 nearest the inner end of the arm.

From the foregoing it will be seen that since 65 the spring 22 is under a degree of tension at all times, the arm 11 will always be held firmly against movement, and thus the elements of the handle will be kept from rattling in whatever positions they may be disposed. It will also be apparent that when the arms 11 carrying the hand 70 grip bar 16 are raised to horizontal or operative position, they will be fixed, and will remain in this position at all times, and in order to insure the maintenance of the arms in raised position the screw 10 is inserted into one of the out-pressed 75 portions 9 and into the threaded opening 21 of

a lug 20, as illustrated in Fig. 4. While in the present description and illustration of the drawing a single hand grip bar has been illustrated and referred to, it is to be understood that this represents one of several of such arms which may be 5 employed in association with a single bar of the type usually employed and which extends throughout the length of the casket.

What is claimed is:

1. A foldable handle of the character described, 10 comprising a body having a socket opening, a hand grip, and an arm carrying said hand grip, and having an end secured in said opening for both oscillatory and longitudinal reciprocatory movement whereby the hand grip may be disposed in either operative or inoperative relation with the body.

2. A foldable handle, comprising a body having an opening, a shell having three sides bordering the opening, a hand grip, an arm having an end 20 extending into the opening through the shell and carrying the hand grip at its other end, and means coupling the said first end of the arm between two sides of the shell permitting reciprocatory and oscillatory movement of the said first end 25 of the arm in the opening.

3. A foldable handle, comprising a base body, means forming a shell carried by the body and having a top wall and side walls, an arm having an end disposed between said side walls, means 30 coupling the said end of the arm with said side walls whereby the end has oscillatory and reciprocatory movement in the shell, a hand grip carried by said arm, and means whereby the arm is locked against oscillatory movement when it 35 is oscillated and reciprocated in one direction relative to the shell.

4. A foldable handle, comprising a base body, a shell carried by and projecting from the base and having an open outer and lower side and 40 top and side walls, an arm having one end disposed between the side walls, connecting means between the arm and the side walls permitting oscillatory and limited reciprocatory movement of the arm, a hand grip carried by the arm, and 45 coacting members carried by the arm and the said side walls which interlock when the arm is oscillated and reciprocated in one direction relative to the shell.

5. A foldable handle, comprising a base body, 50 a shell carried by and projecting from the base and having an open outer and lower side and top and side walls, an arm having one end disposed between the side walls, connecting means between the arm and the side walls permitting oscillatory and limited reciprocatory movement of the arm, a hand grip carried by the arm, means forming a recess in each of said side walls, and a lug carried 55 upon each side of said arm for engagement in a recess when the arm is oscillated and reciprocated 60 in one direction relative to the shell.

6. A foldable handle, comprising a plate body, having an opening therein, an arm having an end disposed in said opening, a pin secured to extend 65 across said opening and passing transversely through said arm, the arm having a slot extending longitudinally thereof in which said pin is located whereby the arm has oscillatory and limited reciprocatory movement on the pin facilitating positioning of the arm at right angles to 70 or in side-by-side relation with the plate, means for locking the arm against movement in the said right-angular relation with the plate, and a hand-grip carried by the arm.

7. A foldable handle, comprising a plate body 75

having an opening therein, an arm having an end disposed in said opening, a pin secured to extend across said opening and passing transversely through said arm, the arm having a slot extending longitudinally thereof in which said pin is located, whereby the arm has oscillatory and limited reciprocal movement on the pin facilitating positioning of the arm at right angles to or in side-by-side relation with the plate, means for locking the arm against movement in the said right-angular relation with the plate, a hand-grip carried by the arm, and resilient means connected with the arm and constantly resiliently holding the arm against movement when in either of the two positions relative to the plate.

8. A foldable handle, comprising a plate having an opening, a shell having an open front and underside and a top and side walls, the said walls bordering the opening and projecting from the plate, an arm having an end disposed between said side walls and adapted to extend into said opening, said arm having a longitudinally extending slot therein and passing transversely therethrough, a pin carried by said side walls and passing through said slot, a hand grip carried by the arm, and a spring secured at an end to said pin and having its other end secured to the arm and constantly urging the arm in a direction to maintain the pin in one end of the slot.

9. In a handle structure, a body having an opening therein, an arm having an end adapted to enter said opening, means supporting the arm from said end whereby the arm may have swinging and longitudinal reciprocatory movement to effect the insertion of said end into or its removal from the opening, and means limiting the further swinging movement of the arm when the same has been moved into operative position.

10. In a handle structure, a body having an opening therein, an arm having an end adapted to enter said opening, means supporting the arm from said end whereby the arm may have swinging and longitudinal reciprocatory movement to effect the insertion of said end into or its removal from the opening, and resilient means connected with the arm and operating to urge the same to the limit of its movement after the arm has been shifted into its operative or inoperative positions.

11. In a handle structure, a carrier body having an opening therein, a handle arm having an end adapted for insertion into said opening, means coupling the arm adjacent said end with the body and permitting the arm to have both swinging and longitudinal reciprocatory movement whereby the said end may be swung into and out of said opening and simultaneously moved longitudinally relative thereto, and means for limiting further movement of the arm after it has been moved to one of its positions of adjustment.

12. In a handle structure, a carrier body having an opening therein, a handle arm having an end adapted for insertion into said opening, means coupling the arm adjacent said end with the body and permitting the arm to have both swinging and longitudinal reciprocatory movement whereby the said end may be swung into and out of said opening and simultaneously moved longitudinally relative thereto, and means carried by the arm for contacting an edge of said opening at the beginning of the movement of the arm in one direction to influence the direction of continued movement.

WILLIAM FREDERICK SHEELEY.
